UNITED STATES PATENT OFFICE.

LOUIS D. GREGG, OF HACKENSACK, NEW JERSEY, ASSIGNOR TO THE GREGG COMPANY, LIMITED, OF NEW YORK, N. Y., A CORPORATION OF NEW YORK.

CAR COUPLER.

Application filed April 30, 1926. Serial No. 105,658.

This invention relates to a link and pin coupler of the type carrying, in addition to a coupling-pin, a link which is locked within the chambered head of the coupler to 5 slide to a limited extent, either forwardly to project therefrom in operative position or rearwardly so as not to interfere with the entry and the pinning therein of the projecting link of the coupler of another car; and 10 the object thereof is to further improve such couplers both structurally and functionally.

To this end, the invention comprises, as one of its features, a coupler with separable base and head, the head being telescopically 15 mounted upon the base, and two interposed springs which will be compressed when the head is moved either towards or from the base and which thus yieldingly lock the two parts together. These two springs are 20 located on the opposite sides of the coupler and are there housed within walls which are carried by the base and head respectively and provide the telescopic connection between these parts and which are spaced apart a 25 substantial distance so as to provide, between the outer faces of the inner walls, a central passage or chamber wide enough to receive the coupling-link and at the same time to permit of the insertion of the springs, at each 30 side, through openings in these inner walls. The opening for the spring in the wall bounding the central passage on each side, usually carried by the head, is preferably provided at its opposite ends with project- 35 ing flanges by which the spring, inserted under compression allowing it to pass between the two flanges and then expanding against the seats provided, will be held locked in place.

40 Other features of the invention, applicable alike to link and pin couplers with separable base and head and to those having an integral draw-head, include an opening of substantial size in the top of the coupler in 45 communication with the rear end of the link chamber, a rear floor section for the link chamber the surface of which curves upwardly and rearwardly at its rear end whereby, when the link is retracted, its rear inner 50 end will be directed upwardly and out through the opening, and, preferably, a transverse notch or projection in the floor of the link chamber into or behind which the front end of the link will drop when at or 55 near the limit of its rearward movement and

so hold the link in its retracted or inoperative position; a coupling-link which is heavier at its inner than at its outer end, so that the projecting outer end of the link at the limit of its forward movement within the 60 head will be overbalanced by such heavier inner end and thereby normally held in a substantially horizontal position, and is preferably provided at its inner end with a hook or handle by which it may be grasped and drawn 65 backwards and upwards through the rear opening in the top of the coupler; a locking-pin, of novel design, which at one end is pivot- 70 ed in a wall of the coupler to swing to a limited extent forwardly and rearwardly within the link chamber and, passing at its free end through the link, serves at the limit of its forward movement as a pivot for the link near the front outer face of the coupler and at the rearward limit of its movement pre- 75 vents the removal of the link from the coupler through the upper rear opening; and, finally, a coupling-pin which is not only locked in the coupler, so that it cannot be 80 lost or stolen, but, when raised to inoperative position, can be tipped back so that it will be held up by gravity and friction but will be jarred loose by the impact of the coupler with the coupler of another car and so drop 85 automatically.

One practical embodiment of the several features of the invention is shown, by way of illustration and not of limitation, in the accompanying drawings, in which—

Fig. 1 is a view, in longitudinal vertical section on the line 1 1 of Fig. 2, of a coupler in which are combined all of the novel features above outlined; Fig. 2 is a view thereof, partly in plan and partly in horizontal longitudinal section on the line 2 2 of Fig. 1; Fig. 3 is a perspective view of one-half of the base of the coupler; and Fig. 4 is a similar view of one-half of the separable head.

Referring to the drawings, A indicates the base and B, the head, of the coupler, C C indicate the two buffer-springs, and D E and F indicate the coupling-link, the locking-pin, and the coupling-pin, respectively.

The base casting provides a vertical base-plate 1 with holes 2 2 for the bolts 3 3 by which it is attached to the underframe of the car. On each of its opposite sides this base-plate carries, spaced apart a substantial distance and set forward from its base on upper and lower legs 4 and 5, upper and low-

er horizontal walls 6 and 7 and connecting vertical walls 8 and 9 which form an elongated spring chamber open at its sides transversely of the coupler. The rear wall 8 is provided with a hole 2' of a size to permit the end of a fastening bolt to pass therethrough. Intermediate these projecting walls and suitably spaced therefrom on each side is a curved shelf or rear flooring for the coupling-link, which preferably as shown is also carried by the base-plate but may be made as a part of the head. For lightness and strength, this shelf is cut away centrally so as to leave two floor ledges or sections 10 and 10 and a thin web 11 connecting them together at the bottom. Each of the two floor ledges, which are alike, is provided at its lower forward end which projects beyond the rear walls 8, immediately below the level of the lower walls 7, with a recess 12, open at the top and on its inner side, and from this forward end its upper surface 13 extends in a concave curve rearwardly and upwardly back to the base-plate.

The head, also an integral casting, may be described generally as a shell, symmetrical on the opposite sides of its vertical longitudinal center, providing face, outer and inner side, bottom and top walls which divide the interior thereof into and more or less enclose a central longitudinal chamber or passage, open front and rear, in which are housed the coupling-link and the locking- and coupling-pins mounted in the top or roof above, and, on opposite sides of said central passage and in communication therewith, two similar side chambers open at the rear to telescopically receive the walls carried on the opposite sides of the base-plate.

The face wall 15 has a central opening 16 which provides between its outwardly bevelled sides 17 a laterally extended mouth or entrance to the central passage and at the bottom a forward extension of the floor of said passage. This wall is curved rearwardly on each side of the head and, dropping somewhat at the top, merges into an outer side wall 18, which is rounded outwardly about a horizontal longitudinal axis into a partial cylinder closed within by segmental ends 19 and 20, with vertical inner edges, spaced the same distance apart as are the walls 8 and 9 of the base. Each of the inner side walls consists of two narrow sections or uprights 21 which parallel the vertical edges of the ends 19 and 20 and are spaced therefrom sufficiently to allow the walls 6, 7, 8, and 9 of the base to pass freely between them; and these two sections are themselves spaced apart to provide an opening of a length from front to rear equal to the distance between the ends 19 and 20, which opening is reduced somewhat at each end, on the side adjoining the central passage, by an upright flange or projection 22

on each wall section. The lower wall has on each side of the head a section 23 with horizontal surface which provides a horizontal floor for each side chamber and, between these side sections, has an intermediate section 24 the upper surface of which serves as the floor of the central passage and, preferably as shown, is inclined forwardly and upwardly at a slight angle. This intermediate floor section is cut away centrally thereof to form at the back of the face wall a transversely elongated rounded opening 25 for the coupling-pin, a rear opening 26, with sides which from its forward end sweep outwardly and back to the inner side walls, of a size to receive the floor ledges or sections 10 carried by the base-plate, and a restricted passage 27 connecting these two openings over the upper face of a transverse web 28. The upper wall has on each side of the head a horizontal roof section 29 for each of the side chambers the lower surface of which parallels the floor surface 23 and is spaced apart therefrom so that together these surfaces will provide free slide bearings for the walls 6 and 7 of the base. The intermediate central section of the upper wall, cut away at the rear over the rear opening in the lower wall, is further cut down and through to form, at the back of the face wall and in vertical alignment with the opening 25 in the floor, an opening 30 for the coupling-pin which is somewhat enlarged rearwardly just below the top surface so as to undercut this surface and form flanges 31 thereat, and, for the mounting of the locking-pin, a parallel-sided opening 32 which extends forwardly into the opening 30 and rearwardly at an incline 33 through the lower part of the transverse bridge-wall 34, with forwardly inclined upper face 35, and is extended laterally to provide trunnion sockets 36 open at the top and connected forwardly with the opening 30 by forwardly inclined grooves 37 in the intermediate wall, the upper sides of these grooves providing retaining shoulders 38 just below the flanges 31.

To assemble these main parts of the coupler, the walls carried on the opposite sides of the base are pushed into the side chambers of the head until they reach the relative position, shown in Figs. 1 and 2, where the inner faces of the walls 8 and 9 register with the inner vertical edges of the inner wall sections 21. The two springs C C are then compressed and slipped first one and then the other between and past the flanges 22 into the two side chambers and, released therein, seat themselves at one end against a wall 8, a segmental end 19 and the edge of one inner side wall section 21 and at its other end against a wall 9, a segmental end 20 and the edge of the other inner side wall section 21. The two springs will

thus normally but yieldingly hold the head upon the base in the position shown, but one or both will be compressed, between the walls 9 and the segmental ends 19 and edges 5 of the two rear wall sections 21 or between the walls 8 and the segmental ends 20 and edges of the two forward wall sections 21, whenever the head is either pushed back upon the base or is pulled forward thereon.

10 The special coupling-link D here provided is weighted at its inner end by a solid extension 40, which terminates in an upwardly and forwardly projecting hook or handle 41. This weight serves to hold the inner end of the link down upon the floor of the head, as shown in Fig. 1, and so to prevent its outer end from dropping of its own weight when projected out from the head to operative position while allowing it 20 to be pulled downward; and the hook or handle thereon, which can be reached by the hand through the opening provided in the top of the coupler, serves as a means for drawing the link back and up to inoperative 25 position where, as indicated by dotted lines in Fig. 1, its outer front end is held in the two recesses 12 12.

The locking-pin E is pivotally mounted at its upper end within the opening 32 in 30 the upper wall of the head, to swing forwardly and rearwardly, by means of integral trunnions 45 which are journaled in the rounded bottoms of the trunnion sockets 36; and, extending downwardly between 35 the sides of and through the coupling-pin, its lower end swings back and forth between the openings 25 and 26 in the lower wall through the connecting passage 27. From about midway of its length downward to its 40 lower end this pin gradually expands both front to back and laterally, and its front face is cut away to provide a vertically-disposed groove 46, with rounded bottom and of gradually increasing depth and of a 45 width to receive the coupling-pin F, the sides of which form, at the lower end of the pin, forwardly projecting arms 47. Thus, when the coupling-link is thrust forward it will carry the lower end of the locking-pin forward with it until the bottom of the groove 46 and the arms 47, which will straddle the coupling-pin when in its downwardly extended position, bear respectively against and are stopped either or both by the coupling-pin and the front of the opening 25 50 at the back of the face-wall. In this position this pin will act as a pivot-pin for the link close to the face of the coupler, as shown in Figs. 1 and 2. The locking-pin 60 will be swung rearwardly when the link is drawn back and up to inoperative position, but, as its rearward swing is limited by a stop provided by the inclined face 33 on the bridge-wall 34, it will prevent the removal of the link from the head.

The coupling-pin F is provided, in addition to the usual shoulder 51 at its upper end or head, with a headed tip 50, preferably of truncated cone shape as shown, which forms at its end a reversed shoulder. This shoulder, when the pin is raised in the head, abuts against the flanges 31 at the upper end of the opening 30 and the shoulders 38 and so locks the coupling-pin to the head, preventing its removal therefrom. The coupling-pin when raised may be tipped back so as to rest against the inclined face 35 of the bridge-wall 34, as indicated in dotted lines in Fig. 1, and will there be held by friction with this face and the friction of the conical surface of its tip with the front of the opening 30. A jar in longitudinal direction, as by the impact of the coupler against the coupler of another car, will however release the pin so that it will drop down to position, as shown in Fig. 1.

The locking- and coupling-pins are assembled and locked in the head in the following manner: The locking-pin is introduced into the central passage in the head and is turned about at an angle of ninety degrees to normal so that the trunnions at its upper end will extend forwardly and backwardly instead of transversely. Thus positioned the trunnions are passed up through the two connecting openings 30 and 32, and, when they are above the head, the locking-pin is turned back to its normal position and the trunnions are dropped into the trunnion sockets. The coupling-pin is then inserted, in the top of the head, by tipping its upper end forwardly and sliding the shoulder at its tip down through the inclined grooves 37 into the opening 30. After this has been done, both locking-pin and coupling-pin are locked in the head by inserting a bolt 60 in the holes 61 provided therefor, thus closing the opening 32 above the locking-pin and the passageway through the grooves 37.

While I have shown and hereinabove described in detail a coupler of the construction which I now prefer and which I now consider to be the best because embodying all the features of my invention, it will be understood that the coupler may be variously modified in the form of its several parts, or by the substitution of equivalents therefor, and that as hereinabove suggested the different features constituting the invention may be used separately or may be differently combined, without departing from the spirit or sacrificing the substantial advantages thereof.

What I claim as new, and desire to secure by letters patent, is—

1. A car coupler of the type described comprising base and head sections telescopically joined on the opposite sides of the coupler and springs yieldingly holding the sections in normal relationship one upon the

130

other in which the head has a solid central buffer face and head and base provided between the springs a link chamber open at its outer end through the buffer face of the 5 head and adapted to receive therein an independent coupling link.

2. A car coupler of the type described comprising a base, a head, and a plurality of 10 springs, in which the base and head are telescopically joined on opposite sides of the coupler and both base and head have integral parts engaging each end of the springs to thereby compress the same upon movement of the head towards or away from the base.

15 3. A car coupler of the type described comprising telescopically joined base and head sections and a spring operatively positioned to be compressed by a movement of one of the sections towards or from the 20 other, the sections providing a spring chamber having for the introduction of the spring a lateral opening of fixed length less than the distance normally separating the spring seats at the ends of the chamber.

25 4. A car coupler comprising base and head sections, a spring cooperatively related to said sections to be compressed by the movement of one thereof towards or from the other, and means for locking the spring in 30 such cooperative relationship including two spaced projections integral with one of said sections and forming the ends of an opening of restricted length through which the spring must be passed under partial compression.

35 5. A car coupler comprising base and head sections which on each of their opposite sides carry bearing surfaces longitudinally telescoping the bearings on one section with- 40 in those on the other section and spaced apart to provide an intermediate central chamber adapted to receive a coupling-link and two springs which are housed one within each of said telescopic joints to bear at each end 45 against a seat provided by integral parts of the base and head sections.

6. A car coupler comprising base and head sections which on each of their opposite sides are telescopically joined by bearing 50 walls sliding longitudinally the bearing walls of one section on those of the other and spaced apart to provide a central chamber adapted to receive a coupling-link, the walls of each of said telescopic joints being 55 adapted to house a spring bearing at each end against a seat provided by integral parts of the base and head sections and providing at the side of the central chamber an opening of restricted length through which the 60 spring must be introduced under compression and by which it will be retained therein when seated.

7. A car coupler comprising base and head sections telescopically joined on each of their

opposite sides to slide longitudinally one up- 65 on the other and providing an intermediate longitudinal chamber adapted to receive a coupling-link and two springs operatively positioned one within each of said telescopic joints to be compressed by the movement of 70 the head towards or from the base, the said longitudinal chamber being open at the front in the face and at the rear in the top of the coupler and having a rear floor section curved upwardly and rearwardly below the rear opening.

8. A car coupler comprising a base and separate head telescopically joined on each of their opposite sides by walls which slide longitudinally the walls of one part within 80 the walls of the other part and two springs mounted one on each side of the coupler within said telescoping walls to yieldingly hold the parts in normal position one upon the other, the side jointure walls being spaced apart to form an intermediate central chamber adapted to receive a coupling-link which chamber, open at its forward end in the face of the head, through the forward portion of its length is provided with a roof and a substantially horizontal floor both carried by the head and through the rear portion of its length is open at the top and has an upwardly and rearwardly curved floor carried by the base.

9. A car coupler of the type described comprising telescopically joined base and head sections and springs yieldingly holding the sections in normal position one upon the other, the sections so joined providing a central link chamber open at its forward end in the buffer face of the head and at its rear end through one of its lateral walls.

10. A car coupler of the type described having telescopically joined base and head sections and springs yieldingly holding the sections in normal position one upon the other, the sections providing a central link chamber open at its forward end in the buffer face of the head and at its rear end through the upper wall of the base and provided within the base with a bottom wall rearwardly and upwardly inclined towards such rear opening.

11. In a car coupler, the combination of 115 a longitudinal chamber adapted to slidably receive a coupling-link and having a rear opening in one side thereof, a link slidable therein, and means for deflecting the rear end of said link when moved backwardly within the chamber through said rear opening.

12. A link and pin coupler comprising a longitudinal link chamber open at the front in the face and at the rear in the top of the coupler and having a rear floor section curving rearwardly and upwardly below said rear opening and provided with a trans-

verse recess at the bottom of said incline adapted to receive the end of a coupling-link.

13. A link and pin coupler comprising, in combination, a longitudinal link chamber open front and rear, a coupling pin mounted in holes in the upper and lower walls of the chamber near the forward end thereof, a link of loop formation mounted to slide 10 within the chamber, and passing through the loop of the link a member locked within the chamber to move within fixed limits therein, forwardly to a position immediately behind the coupling pin where it serves 15 as a pivot pin for the link and rearwardly to allow the link to project through the rear opening of the chamber while locking it against removal therethrough.

14. A link and pin coupler comprising, in combination, a longitudinal link chamber open front and rear, a link mounted to slide therein, and passing through the loop of the link a member mounted pivotally in a wall of the chamber to swing forwardly and rearwardly within fixed limits therein thereby permitting the link to shift longitudinally to project through while locking it against removal from either front or rear chamber opening.

15. A car coupler comprising a longitudinal link chamber open at the front in the face and at the rear in the top of the coupler and having a rear floor section curving rearwardly and upwardly below the rear opening, a link of loop formation mounted in said chamber to slide therein, and a pivotally mounted member passing through the loop of said link and adapted to lock the rear end of the link within the forward end of the chamber and the forward end of the link within the rear end of the chamber against removal through either opening.

16. A car coupler comprising a longitudinal link chamber open at the front in the face and at the rear in the top of the coupler and having a rear floor section curving rearwardly and upwardly below the rear opening, a link of loop formation mounted in said chamber to slide therein, a pivotally mounted member passing through the loop of said link to swing forwardly and rearwardly to a limited extent only and adapted to be so swung by the engagement therewith of the ends of the link when moved forward and back within the chamber and on reaching the limit of its movement in either direction to lock the link against further movement in that direction, and means adapted to engage and hold the front end of the link 55 against forward movement when near the permitted limit of its rearward movement.

17. A car coupler comprising a longitudinal link chamber open at the front in the face and at the rear in the top of the coupler and having a rear floor section curving up-

wardly and rearwardly below the rear opening, a coupling-link of loop formation mounted to slide within the chamber, a member pivotally mounted in the walls of the coupler over the chamber and adjacent its forward end to swing forwardly and rearwardly therein with its lower free end extended downwardly through the loop of the link, a stop adapted to engage the lower end of said member and to limit its forward movement when in a position substantially parallel to the face of the coupler, and a second stop adapted to engage said member to limit its rearward movement near the rear opening of the chamber.

18. A car coupler comprising a longitudinal link chamber open at the front in the face and at the rear in the top of the coupler, a coupling-link of loop formation slidable within the chamber, and a locking member extending downwardly through the chamber and coupling-link and pivoted at its upper end, to swing to a limited extent forwardly and rearwardly within the chamber without withdrawal from the coupling-link, by means of integral trunnions journaled in trunnion sockets in the sides of a longitudinally elongated opening in the walls of the coupler above the chamber permitting the trunnions of the locking member to be passed therethrough and when above the top of the coupler to be turned about and dropped into the trunnion sockets.

19. A link and pin coupler comprising a link chamber open at its outer front end in the face of the coupler between upper and lower buffer walls of substantial height and a link of loop formation so slidably secured within the chamber that it may project for a considerable portion of its length outwardly beyond the coupler face, the link being integrally weighted at its inner end and supported by the floor of the chamber substantially to the face of the coupler whereby the outer end of the link when fully extended will normally be held in horizontal position while capable of being tilted up and down therefrom and of swinging laterally to a substantial degree.

20. In a link and pin coupler, the combination of a longitudinal link chamber open at the front in the face of the coupler and at the rear through an opening in the top of the coupler large enough to admit the hand of an operator, and a coupling-link provided at its inner rear end with projecting means serving as a handle whereby the link can be grasped and drawn upwardly through said rear opening.

21. A link and pin coupler comprising a longitudinal link chamber open at the front in the face and at the rear in the top of the coupler and a coupling-link slidable in said chamber and capable of projecting for a portion only of its length through said front

70

130

opening, the rear opening being of a size to admit the hand of an operator and the inner end of the link being provided with an upward offset by which the link can be 5 grasped and drawn up and back through said rear opening.

22. A link and pin coupler comprising a longitudinal link chamber open at the front in the face and at the rear in the top of the 16 coupler and having a substantially horizontal front and a rearwardly and upwardly inclined rear floor section, and a coupling-link weighted and provided with a handle at its inner end slidably mounted in said chamber and limited in its movement therein so 20 that its forward portion only can project through the front opening and its rear portion only can project through the rear opening of the chamber.

23. A pin and link coupler comprising a longitudinal link chamber open at its front end in the face of the coupler and provided near the face of the coupler with holes in the upper and lower walls of the chamber to 25 receive a coupling pin in which the hole in the lower chamber wall is elongated transversely of the chamber to permit a substantial lateral movement of the pin therein and the hole in the upper chamber wall is adapted to hold the upper end of the pin substantially at the transverse center of the chamber while permitting its lower end to swing laterally within the hole below.

24. A car coupler comprising a longitudinal link chamber open at the forward end of the coupler, a coupling-pin provided with shoulders both at its head and tip, an open-

ing in the walls of the coupler at the bottom of the link chamber adapted to receive the shouldered tip of the coupling-pin, an opening in the walls of the coupler at the top of the link chamber adapted to receive the coupling-pin and reduced in size at its upper end to prevent the passage therethrough of either shoulder of the pin, a passage from 40 the top of the coupler connecting with one side of the upper opening adapted to admit the shouldered tip of the coupling-pin to 45 said opening below its contracted upper end, and means for closing said passage. 50

25. In a car coupler, the combination of a link chamber open forwardly in the face of the coupler, a link, a locking-pin with integral pivot trunnions at its upper end, and a coupling-pin with shoulders at both head and tip, and means for mounting and locking both locking- and coupling-pins in the wall of the coupler over the link chamber, a forward opening in said wall of rounded section adapted to receive the coupling-pin 60 and contracted at its upper end to prevent the passage of either shoulder thereon, a second opening with parallel sides opening forwardly into the rear side of the front opening and having in its sides trunnion sockets 65 open at their upper ends, forwardly and downwardly inclined grooves connecting each the forward side of a trunnion socket with the rear side of the forward opening below the contracted upper end thereof, and 70 means for simultaneously closing the upper ends both of the trunnion sockets and of the inclined grooves.

LOUIS D. GREGG.
